ABSTRACT

This invention consists of two horizontally disposed, vertically spaced and parallel plates of the same diameter that are held in the desired position and are connected together by two curved body members having a plurality of integrally formed L-shaped lugs on each end thereof snapped through elongated openings in the plates. A curved head is similarly secured to the upper side of the top plate from which downwardly extends two arms while two legs extend downward from the underside of the bottom plate. The just-described structure, which has the basic configuration of a person, is so mounted on a vertically disposed stick that is held in ones hand that the structure will either be rotated by the action of wind or rotated by movement of ones hand.

WIND POWERED SPINNING TOY

This invention relates to toys; more particularly, to wind-powered spinning toys; still more particularly, to toys having the basic configuration of a person.

It is the principal object of this invention to provide a wind-powered spinning toy having the shape of a person which, when held in a vertical position in the hand, will be spun in the horizontal plane by either the action of the wind or by the movement of the hand.

Another object of this invention is to provide a wind-powered spinning toy that can be packaged in kit form for assembly by the purchaser without the use of glue, paste or sealing tools since the toy is made of different colored plastic or the like, the toy being constructed as herein described.

Still another object of this invention is to provide a wind-powered spinning toy of the character herein described that by its different gyrations will amuse people of all ages.

Other and further objects and advantages of this novel invention will become apparent to even the most inexperienced person in the art upon the reading of the following description of this toy and its appended claims and upon the examination of the accompanying drawing.

In the drawing:

FIG. 1 is a pictorial view of this invention in its entirety.

FIG. 2 is a top view of this invention.

FIG. 3 is an exploded pictorial view of a portion of the invention indicated by the arrowed line and number 3 in FIG. 2.

FIG. 4 is a front view of this invention.

FIG. 5 is a sectional view of this invention, taken substantially along line 5—5 of FIG. 4, and viewed in the direction indicated by the arrows. The two arms are not shown for reasons of clarity.

FIG. 6 is an exploded pictorial view of a portion of that part of this invention that embodies the connection of one of the arms to one of the horizontally disposed plates.

In the several views of this novel invention, like parts of the toy are indicated by like reference numbers. The reference number 10 indicates this invention in its entirety.

Directing ones attention first to FIG. 1 of the accompanying drawing it will be seen that this wind-powered spinning toy 10 consists of a flat top plate 11 and a flat bottom plate 12, the flat bottom plate 12 being of the same diameter as that of the just-mentioned top plate 11. Both of the aforesaid plates have a plurality of V-shaped points around the periphery thereof. Both plates are made of thin sheets of colored plastic, as is the head 13 and also the two curved body members 14 that are the vanes which cause this novel toy to rotate in the wind. The aforesaid body members are located vertically between the aforesaid top plate 11 and the aforesaid bottom plate 12. The invention also embodies two arms 15 and two legs 16.

Before going any further into the description of the construction of this novel invention it should be realized that the invention does not require any glue, paste or the like for its assembly since all of the above noted parts of the toy are locked in place by means of lugs passing through elongated openings in either the aforesaid top plate 11 and/or the aforesaid bottom plate 12.

Directing ones attention now in FIG. 1 of the accompanying drawing it will be seen that the already-mentioned head 13, like top and bottom plates 11 and 12, is made of thin plastic sheet material of any desired color as are the body members 14, arms 15, and legs and feet 16. The lower and outer portions of the aforesaid head 13 are provided with two spaced, parallel, and integrally formed L-shaped lugs which lock into the elongated openings 17 and 18 of the often-mentioned top plate 11. When this is done, the aforesaid head 13 will be curved in the vertical plane, as one can see by looking at FIG. 2 of the drawing. The just-mentioned lugs of the head 13 are identical to the lugs of the aforesaid body members 14, one lug of which is illustrated in FIG. 3 of the drawing.

Continuing to look at the drawing it will be seen and understood that each of the aforesaid body members 14 is provided with lugs 19 that are identical to the just-described lugs of the aforesaid head 13. That is, each body member 14 has two L-shaped lugs 19 which lock into two elongated openings in the aforesaid top plate 11, thus causing the body members to curve. Likewise, the lower edge of each body member is provided with similar L-shaped lugs that lock into similar elongated openings in the aforesaid bottom plate 12. The curved body members 14 are clearly shown in FIG. 5 of the accompanying drawing.

The upper end of each arm 15 and each leg 16 is provided with an integrally formed rounded end 20 having an elongated recess 21 that extends downward for a predetermined distance into the arms 15 and legs 16. This configuration of the upper ends of the arms and legs permits these parts of this invention to be assembled into the proper elongated openings in the upper or lower plates of the toy, as one can fully understand by looking at the various Figures of the accompanying drawing.

Although it has not been previously mentioned it will be understood, by those experienced in the art upon the reading of the above-described description of this invention, that to assemble the aforesaid head 13 and the two body members 14 to the aforesaid top plate 11 and bottom plate 12 it will be necessary to squeeze or bend the head and body members slightly in order to snap the lugs of these parts into the elongated openings in the plates which thus hold the just-mentioned head and body members in the desired position without any danger of the same from falling out.

When this novel invention is assembled as above described, a stick of wood or the like 22 of any desired length is inserted into the centrally located opening 23 in the aforesaid bottom plate 12 and pushed on up through the body of the toy to the top plate 11 where a headed (beaded) pin 24 is pushed down through the top plate 11, thus fastening the body of the toy on the stick in such manner that the body of the toy will freely rotate on the stick 21 since the aforesaid opening 23 in the bottom plate 12 is larger in diameter than that of the aforesaid stick 22, as can be seen on examination in FIG. 1 of the accompanying drawing.

It is noted that body members 14 are curved and arranged in such a way that they serve as vanes to cause the toy to rotate. Also the curvature of head 13 is such that said head will act as a vane to assist body members 14 in causing rotation of the toy.

The invention is so constructed that the toy can swing in any direction including upside down, to the right or to the left. The toy can either be rotated by the wind, or by ones hand, all of which is clearly understood by those experienced in the art when one has examined FIGS. 1 and 4 of the drawing.

This invention is subject to any and all changes and/or modifications that one may care to make. The toy can be provided with any shaped head or other body members in so long as the changes and/or modifications all fall within the scope and intent of the appended claims.

What I now claim as new and desire to secure by Letters Patent is:

1. A wind powered spinning toy of the character described, which may have the configuration of a person, the toy comprising two horizontally disposed, vertically spaced and parallel plates having a head secured to the upper side of the top plate, two arms extending down from the said top plate, and two legs extending down from the bottom plate, the two plates being suitably secured together by two vertically disposed body members, one body member being concave and the other convex when viewed from the same direction whereby said body members will serve as vanes to cause the toy to rotate; and vertically disposed structure adapted to support the said toy in ones hand where it can either be spun by the wind or by the action of ones hand.

2. The invention of claim 1 wherein, with the exception of the said structure, all of the members of the said

toy are made of thin sheet plastic material of one or more desired colors.

3. The invention of claim 2, wherein both the said top plate and the said bottom plate are provided with a plurality of elongated openings in which are snapped lugs or the like that are integrally formed on the ends of the said body members which are each curved when viewed from the top when the said toy is assembled.

4. The invention of claim 3, wherein the said head is likewise provided with a plurality of integrally formed lugs that are likewise snapped into elongated openings in the said top plate in such a manner as to curve the said head vertically when the said head is secured to the said top plate.

5. The invention of claim 4, wherein the upper end of each arm and each leg is provided with a knob adapted to be snapped into place in an elongated opening in the proper plate when the said invention is assembled, each said arm and leg having an elongated recess extending downward from the top of its knob for a predetermined distance down into the arm or leg.

6. The invention of claim 5, wherein the said bottom plate is provided with a centrally located opening through which upwardly projects structure in the form of a stick or the like that is slightly smaller in diameter than that of the opening, the top of the said stick being secured to the underside of the said top plate by a headed pin that projects downward through a centrally located opening in the said top plate thus permitting the said toy to spin about the said stick.
